UNITED STATES PATENT OFFICE.

JOSEPH OLMSTED, OF NEW YORK, N. Y., ASSIGNOR TO THE UNITED STATES ELECTRIC LIGHTING COMPANY, OF SAME PLACE.

ELECTRIC-ARC LAMP.

SPECIFICATION forming part of Letters Patent No. 279,103, dated June 5, 1883.

Application filed January 6, 1881. (No model.)

To all whom it may concern:

Be it known that I, JOSEPH OLMSTED, a citizen of the United States, residing at New York, in the county of New York and State of New York, have invented certain new and useful Improvements in Electric Lamps; and I do hereby declare the following to be a full, clear, and exact description of the invention, such as will enable others skilled in the art to which it appertains to make and use the same, reference being had to the accompanying drawings, and to the letters or figures of reference marked thereon, which form a part of this specification.

15 My invention relates to electric-arc lamps, and is designed to improve the sensitiveness and power of the magnet system which controls the movements of the feed-regulating devices for the carbon or carbon-carrier.

20 My invention consists in the combination, with feed-regulating mechanism of any proper kind, of an electro-magnet in the main or principal circuit with the arc and an electro-magnet in a derived circuit of comparatively 25 high resistance around the arc, having its pole or poles presented to the pole or poles of the main-circuit magnet, and having its coils so wound or connected as to tend to produce at its pole magnetism of the same sign as that of 30 the pole of the main-circuit magnet.

My invention also consists in the combination, with a main-circuit electro-magnet, of a derived-circuit electro magnet wound in the manner described, whose poles are presented 35 to the poles of the main-circuit magnet, and whose core is constructed to rock on its longitudinal axis, said rocking core being connected to mechanism by which the feeding of the carbons is effected.

40 In carrying my invention into practice I have applied it to a novel construction of feed mechanism, and of mechanism for causing a separation of the carbons to form the arc. Such mechanisms are not, however, herein 45 claimed by me, as I design making them the subject of a separate application for patent.

In the accompanying drawings, Figure 1 is a side view of a complete lamp to which my present invention is applied. Figs. 2 and 4 50 show in end view the controlling mechanism

which is actuated or controlled by the magnet system. Fig. 3 is a side view, and Fig. 5 a plan view, of the same. Fig. 6 is a section on line *x* *x* of Fig. 5. Fig. 7 is a detail view in section of the lower-carbon holder. Figs. 8 55 and 9 are views of details. Fig. 10 is a diagram showing the circuits of the lamp. Fig. 11 is a plan of the bottom of the lamp; and Fig. 12 is a side view of a portion of the mechanism for lifting the upper carbon to form the 60 arc. Figs. 13 and 14 are views of the mechanism for feeding the carbon and for lifting the carbon, detached from the other parts.

O is any suitable base, preferably of wood or other insulating material, upon which the 65 regulating devices are mounted, and from which the lamp proper is suspended. From the base O depend the two rods G G', attached at their lower end to the cross-piece G'', which supports the lower-carbon holder.

Upon the lower side of base O is fixed the 70 resistance-coil P', to be hereinafter described. This coil is formed as a cylinder to permit the passage through it of the upper-carbon holder f, which is a tube having its upper portion 75 formed into or with a rack. Above the base O it passes into another tube, F', having a hook at its upper end for the suspension of the lamp. The tube F' is jointed at F'', in order that the upper portion may be detached to 80 permit the ready and easy introduction of the carbon pencil into f, the carbon being secured therein at its upper end by the screw-clamp F.

Dependent from the base O and around the tube f are three or more rods, h, united by a 85 base-piece at their lower ends, which base-piece is perforated to admit of the carbon passing through it. These rods h and their perforated base-piece constitute a guard-frame which supports and steadies the carbon just 90 above the point of illumination, and also, being electrical conductors, afford a path for the current of little resistance to a point on the carbon near the arc, thus avoiding the greater portion of the resistance of the upper carbon. 95

The lower-carbon holder is supported upon the cross-piece G'', and is constructed in the manner shown in detail in Fig. 7.

In the enlarged central portion of G'' is an opening, in which is placed the sleeve Y', some- 100

what smaller in diameter than the opening through which it passes, thus allowing of a lateral adjustment by which the lower carbon may be brought into exact alignment with the 5 upper carbon.

The upper portion of the sleeve is provided with an enlarged head or flange, Y, and its lower end is screw-threaded externally, and carries a clamping-nut, W, which, in conjunction 10 with the head Y, resting upon G", serves to secure the sleeve and the supported carbon in position after lateral adjustment.

Within the sleeve Y' is a sleeve, U', capable of vertical movement therein. Its lower portion is screw-threaded for the reception of an 15 adjusting-nut, V, whose upper face bears against the nut W, while the screw-thread upon its upper portion serves as a means of attachment for the carbon-clamp, U, a downward 20 extension from which is provided with an internally screw-threaded ring or collar for engagement with the upper portion of U'. A pivoted clamping-jaw, x, pivoted to U, has a tail-piece whose end, as shown, is formed with 25 a beveled face resting upon a bevel, y, upon the upper portion of Y. The lower carbon or carbon-carrier is clamped between the jaw x and the part U.

The operation of these devices is as follows: 30 The nut V having been loosened, the sleeve U' may be raised, and the upper portion of the jaw x may be then opened so as to allow the insertion of the lower carbon. To clamp the carbon the nut V is turned so as to draw down 35 the sleeve U', and its attached parts, thereby carrying the beveled tail-piece of x down upon the incline y, so as to force the jaw x into firm contact with the carbon, thereby clamping it firmly between x and U. The annular 40 depression in the upper face of the head Y serves as a holder for the ordinary opalescent globe.

As before stated, the upper-carbon holder passes above the base and is formed into or 45 with a rack, so that a pinion taking therein may elevate or depress it. Taking into it is a pinion, 8, formed on the same sleeve as the gear 6, (see Figs. 7 and 8,) the sleeve being loosely mounted on the shaft 9, supported in 50 suitable bearings. Upon the opposite end of the shaft 9, and loose thereon, are a gear, 5, and pinion 12, likewise formed on the same sleeve. Upon the same shaft is the planet-wheel 4, with a groove in its periphery, and having let into 55 it the pinion 7, into which take, on opposite sides, the gears 5 and 6. In the groove upon the face of the wheel 4 is the strip R", one end of which, as shown in Fig. 12, is attached to a collar, N, sliding upon a post, q, and resting 60 upon a spiral spring, M, its other end being attached to the end of the armature-lever R', Fig. 3, whose armature P is acted upon by the electro-magnets C D, (shown in top view in Fig. 5,) which are in the main or light circuit, 65 and which serve, through the intermediate devices, to lift the upper carbon to form the arc.

Upon a shaft, 10, at right angles to the shaft

9, is a worm, 11, taking into the pinion 12. Upon 10 is also secured the smooth friction-wheel 16. Pivoted upon 10, and with its sides 70 encompassing the wheel 16, is the cage 14, pivoted to the link 13, which is in turn pivoted to the lever g, Fig. 9.

Within the cage 14, whose outer end inclines upwardly and outwardly, lies the loose rubber 75 15, between the wheel 16 and the end of the cage 14. The lever g, as shown in Figs. 2 and 5, is an extension from the pole-piece a of an electro-magnet, J, rocking upon its longitudinal axis. The electro-magnet J is in a shunt 80 around the carbon, and its poles a and b are within the magnetic field of the electro-magnets E and D in the main or light circuit.

The rocking movement of the electro-magnet J, which is brought about in the manner 85 hereinafter described, is communicated to the lever g and cage 14, and serves to feed the upper carbon downward.

The mechanical operation of these devices in adjusting the upper carbon with reference 90 to the lower is as follows: During the upward movements of the link 13, cage 14, and roller 15, the latter, owing to the inclined inner surface of the cage, engages with the wheel 16 and partially rotates the same, turning it a 95 certain definite distance, dependent upon the amount of movement permitted to 14. This movement is capable of adjustment, and may be regulated to give a downward feed to the upper carbon to a very small extent for each 100 oscillation. Upon the downward motion of the cage the roller 15 is released from frictional contact with 16 and simply slides over its surface. An ordinary ratchet-wheel and pawl 105 might be substituted for this friction device. Any device for producing a step-by-step rotary movement in one direction by means of a reciprocating movement may be used in this connection. The wheel 16 imparts a movement to the carbon-carrier through 10 11 12 5 110 7 to 6 8, and thence to the rack on f, moving it a certain definite distance dependent upon the amount of movement permitted to the reciprocating parts.

In lifting the upper carbon the end of the 115 lever R' to which the strap R" is attached is raised, and the strap, being thus brought into firm engagement with the wheel, rotates the same, the sliding collar being at the same time drawn down upon the part q against the force 120 of the spiral spring. The partial rotation thus given to planet-wheel 4 imparts motion bodily to its pinion 7. The wheel 5 being held from movement under these conditions by reason of the frictional locking at the point 125 where the pinion 12 engages with the worm-gear 11, the pinion 7 will rotate on its own axis, and will in turn rotate the gear 6 and pinion 8, which latter, taking into the rack on the carbon-holder f, raises it, separating the 130 carbons. The upper carbon is held against the action of gravity by reason of the frictional contact between the strap R" and wheel 4. The carbon-carrier may be readily raised to

its upper position for the insertion of a fresh carbon when the end of lever R' is depressed and the strap is free from tension.

The electro-magnets C D E (shown in top view in Fig. 5) are mounted upon the base O, and are in the main or light circuit, passing through the carbons. C and D constitute practically one electro-magnet, and act upon the armature P of the lever R' , which serves to separate the carbons. The electro-magnet E, in conjunction with a polar extension from D, acts upon the rocking electro-magnet J. The circuit enters at post A, goes through C, D, and E to metal plate B, metallic gearing mounted upon the plate, to carbon-holder f, to the positive or upper carbon, thence to lower or negative carbon, thence by G" and G' to post H. The armature P of the electro-magnet C D is attached to the lever R' at the opposite end of the strap R'' . Whenever the circuit is closed through the lamp the electro-magnet C D attracts its armature, elevating the other end of the lever R' , causing rotation of planet-wheel 4, separating the carbons, as before described, for the immediate formation of the arc.

Of the electro-magnets C D, one, D, is somewhat shorter than the other, in order that there may be room between the armature P and the coil of D for the core of D to be bent over, first at right angles, then obliquely, and then upwardly, forming the polar extension c , for action upon the polar extension b of electro-magnet J, as shown in Fig. 5. The electro-magnet J is wound with fine wire, so as to be of high resistance, and is in a circuit which is a shunt to the main circuit, or circuit to the electro-magnets C D E and the carbons forming the lamp. One end of its core is prolonged upwardly, so as to form the polar extension b , the other being prolonged horizontally into the polar extension a , whose fore end takes over and forms the armature of the electro-magnet E. Upon this pole a is an insulating-block, g , to whose extension, Figs. 2 and 5, is pivoted the link 13, controlling the motive mechanism 14 15 16, which feeds the upper carbon downward. Upon this block is pivoted the arm K, whose outer end plays between the adjustable stops d d'' upon the standard d . The other end is weighted, as shown, so as to cause the lever K to normally make contact with the contact-point L of the polar extension a . The circuit of the electro-magnet J passes from the binding-post A to the contact L, thence to K, thence to the magnet J, and thence to the post H. When there is not such magnetic attraction existing between E and a as to pull a down, the parts are in the position shown in Fig. 2 and the circuit of J is broken between L and K. When, however, E attracts a the lever K is forced from the stop d' , and its overbalanced end immediately contacts with L, which contact is rendered more forcible by K taking against d'' upon the completion of the movement of a . Thus every movement of a causes a make and break in the circuit of its electro-magnet J, and also through the extension g , a

movement of the lever 13 imparting a movement to the train of gearing before described for feeding the upper carbon downward.

The polar extensions a and b of J are rigidly secured to J, which is pivoted in suitable bearings. Normally it is held in such position that its poles a and b shall be forced away from c and E by springs e and e' , adjusted by set-screw e'' , Fig. 6. It is so wound that its poles would normally be of the same polarity as the adjacent poles—that is, b and c similar and a and E similar, each tending to neutralize the other.

The relative resistances of the shunt and carbon circuits and construction of the coils are such that when the carbons are a proper distance apart the current strength and the magnetic effects in C D E are much greater than in J, and as a consequence the magnetic induction from the poles of D and E upon the core of J is sufficient to overbalance the electro-magnetic effects of the coils of J, and hence the polarity of core of J becomes the reverse of that which it would exhibit if J were allowed to act unopposed. Hence J is attracted by D and E, and the polarity of its core, under these conditions, becomes practically the same as that of a soft-iron armature under the inductive influence of D and E. The counter-inductive effects from D and E normally so far overbalance the effects of coil J that sufficient attraction exists between the poles of J and of D and E to overcome also the tension of the retractile springs acting upon J. Should, however, the resistance at the arc increase, owing to consumption of the carbon and a consequent increase in the length of the arc, less current flows through D and E and more through J, in accordance with well-known laws, and as a consequence the magneto-inductive effects of D and E are diminished, and the counterbalancing or opposing electro-magnetic power of J is increased to such an extent that sufficient attraction does not exist between the cores of J and D and E to overcome the tension of the retractile springs, and J therefore recedes. When this happens the circuit of J is broken at K and L, as before explained, whereupon J ceases to be magnetic, and its poles a and b become simple neutral iron armatures to C, D, and E, which thereupon attract them, causing the re-establishment of the circuit of J at K and L, which operations first lift and then depress 13 and 14, imparting motion to 16, and thence through the connected gearing to the upper-carbon holder, lowering it a small space, diminishing the resistance in the main circuit. These operations are repeated until the normal position of the carbons and the magnetic preponderance of C, D, and E over J are restored. This arrangement of circuits is more clearly shown in Fig. 10, where the magnets are shown disassociated from the devices they operate, in which the main or lamp circuit 11 is shown in full lines passing from post A through E C D carbons c c'' , to post H, while from post A the shunt-circuit 2 2 (shown in

broken lines) passes to L K, electro-magnet J to H.

An additional circuit, 3 3, shown in wavy lines, forms a shunt to both circuits 1 and 2 and their electro-magnets and the lamp, taking the current from both when closed. In this circuit is the cylindrical resistance-coil P', having a resistance of about one-half the lamp-circuit. As shown, this coil encircles the carbon-carrier. This disposition of the coil gives symmetry to the lamp, economizes space, and simplifies the construction. Upon the under side of the base O are two metal pieces, s s', Fig. 3, separated from each other, a wire from 15 P' leading to s, while from s' the wire leads to H, forming a break in the circuit 3.

Attached to the lever R' is a rod, R, insulated from the metallic parts of the lamp, passing through the base O, and carrying on its 20 lower end the cross-piece r, adapted to rest upon the metal pieces s s' and close the break at that point in the shunt-circuit 3 3, and also serving as a back stop to the armature P, preventing it from being drawn too far from the 25 electro-magnets C D.

Between the pieces s s' slides a box composed of metal sides s'' s''', fastened to and insulated from each other by an insulating thumb-piece, S. The sides s'' s''' are beveled at their 30 front ends, so as to readily pass over the cross-piece r and draw down the rod R, locking the armature P and wheel 4. When in this position (shown in Fig. 4) the greater portion of the 35 current passes from one binding-post through the resistance-coil P' s r s' to the other binding-post. If S be drawn back, the cross-piece r would naturally rest on s s', closing the shunt-circuit if no current were on. If, then, the main circuit be closed while a large portion 40 of the current passes through the shunt-circuit 3 3, enough passes through the main circuit to energize the magnets C D sufficiently to pull down the armature P, thus moving r from s s', breaking the shunt. If, however, 45 from any accident, the main lamp-circuit should be broken, the armature P, moving away from C D, again brings r into contact with s s', automatically establishing a circuit around the disabled lamp, so that the operation 50 of other lamps or devices in the same series shall not be interfered with.

In my device it will be observed that the shunt-circuit closer is attached to the armature of one of the regulating electro-magnets. 55 This is a feature of some importance, as it renders the use of an extra electro-magnet for this purpose unnecessary.

Where it is desired to replace either carbon, the upper holder is raised to the proper position, the switch S is slid forward, and its beveled ends, taking over the cross-piece r, pull down the rod R and lever R', which latter, through the strap R'', which is now in close 60 contact with wheel 4, locks said wheel and, 65 through the connected mechanism, the carbon-holder in place. At the same time the cross-piece r completes the circuit 3 from s to s',

cutting off the current from the remainder of the devices. The switch being slid back, the circuit 3 is broken, the armature-lever R is 70 free to be retracted by spring M acting upon collar N, and the wheel 4 is free to rotate, so as to allow the upper carbon to drop into contact with the lower.

The novel magnet system herein described, 75 consisting of the main and derived circuit magnet arranged in the described relation, may assume other forms besides that shown without departing from the spirit of the invention, and may be used in conjunction with 80 other mechanical devices for governing or regulating the feed of the carbon, the method of application to other well-known devices being obvious.

The devices for producing a reciprocating 85 motion of the magnet do not constitute the invention which I desire herein to patent, my present invention being confined to the novel magnet system, and not depending upon any particular devices for controlling or operating 90 the carbon through the movement of the magnet.

The devices herein shown form the subject of a separate application for patent.

I make no claim herein to the clamping devices for the lower carbon, the shunting or short-circuiting devices that operate on an abnormal increase in the length of arc, and the mechanism by which they may be locked, the peculiar mechanical devices used in the feed-regulating mechanism, the cage surrounding the upper carbon, or to the novel combinations of magnets and mechanism whereby the carbons are separated and held separated to form the arc, and are fed downward by a step-by-step movement to compensate for combustion, 105 as these all form the subject of other applications for patent to be filed by me.

What I claim is—

1. In an electric lamp, the combination of 110 an electro-magnet in the main or principal circuit and an electro-magnet in the derived circuit, arranged with its pole in inductive proximity to the electro-magnet in the principal circuit, so as to constitute an armature 115 therefor, and wound and connected, as described; so that the derived-circuit currents tend to produce in the pole of said magnet magnetism of the same sign as that exhibited by the pole of the main-circuit magnet to 120 which it is presented.

2. In an electric lamp, the combination of a 125 main-circuit magnet and a derived-circuit magnet, one of which is mounted, as described, so as to be movable to and from the other, 130 said magnets being wound and connected so that the main and derived circuit currents tend to produce magnetism of the same sign in the poles of the magnets which are presented to one another.

3. An electro-magnet in the main circuit of 130 an electric lamp, having its armature wound with a helix of fine wire of high resistance in a derived circuit in such a manner that when

an increased resistance of the main circuit diverts the electric current into the derived circuit it will tend to convert the armature into a magnet with poles similar to the opposite poles of the electro-magnet.

4. The combination, with a main-circuit electro-magnet, of a separate rocking electro-magnet placed in a derived circuit and mounted on a support independent of the main-circuit magnet, and mechanism connected to said electro-magnet for controlling or causing the feed of the carbon.

5. The combination of separate main and derived circuit magnets, having separate pole-pieces arranged in inductive proximity to one another, and wound and connected in the manner described, so that the derived-circuit coil tends to diminish in its core the magnetism induced from the core of the main-circuit magnet in inductive proximity thereto, and

mechanism for controlling or regulating the feed of the carbons connected to one of said magnets, so as to be actuated thereby.

6. The combination, in an electric lamp, of feed-regulating mechanism and an operating 25 or controlling magnet system comprising two electro-magnets having their poles presented to one another and wound respectively with coils in the main and the derived circuit, one of said magnets being arranged to rock upon 30 its longitudinal axis, and provided with rectangular pole-pieces extending toward the poles of the other electro-magnet.

In testimony whereof I affix my signature in presence of two witnesses.

JOSEPH OLMSTED.
